UNITED STATES PATENT OFFICE

FRANZ SKAUPY, OF BERLIN-LICHTERFELDE, HANS EWEST, OF BERLIN, AND HANS PULFRICH, OF BERLIN-BAUMSCHULENWEG, GERMANY, ASSIGNEES TO GENERAL ELECTRIC COMPANY, A CORPORATION OF NEW YORK

GASEOUS ELECTRIC DISCHARGE DEVICE

Application filed June 4, 1931, Serial No. 542,166, and in Germany July 18, 1930.

The present invention relates to gaseous electric discharge devices generally and more particularly the invention relates to such devices in which the gaseous filling consists wholly, or in part of a common gas.

It is well known in the art that common gas used in gaseous electric discharge devices is "cleaned up" during the operation of the device with disastrous results. For this reason many devices have been resorted to for feeding common gas replenishments to such gaseous electric discharge devices such as the "Moore valve" well known in the art. More recently substances which generate common gas when heated have been used in the container of gaseous electric discharge devices and various means are used to accomplish the heating of these gas evolving substances, such means being described in co-pending applications Serial Number 372,964, filed June 22, 1929, being the invention of Alferd Rüttenauer and Martin Reger; Serial Number 381,036, filed July 25, 1929 being the invention of Marcello Pirani and Kurt Nitschke and Patent Number 1,831,950, granted November 17, 1931 and being the invention of Hans Ewest and Martin Reger. These gas evolving substances commonly consist of a compound of a carbonate and a substance which has a decomposition temperature and pressure of as high a degree as the carbonate, such as beryllium carbonate, potassium carbonate, magnesium carbonate or dolomite.

It has been found that in such gaseous electric discharge devices the carbon dioxide evolved by the carbonate compound is changed in composition under the influence of the electric discharge in said device to form nascent oxygen which is absorbed by the electrodes and the glass walls of the container of the device. The products, other than nascent oxygen, resulting from this decomposition of the carbon dioxide are carbon monoxide, which is gaseous, and carbon suboxide, which is solid. This latter substance collects on the electrodes and on the walls of the gaseous electric discharge device, during the course of time, and forms deposits of light absorbing material thereon. The object of the present invention is to prevent

the formation of carbon suboxide in the container of a gaseous electric discharge device the gaseous filling of which consists wholly or in part of carbon dioxide. A further object of the invention is to prevent the formation of deposits of light absorbing material in such device. Still further objects and advantages attaching to the invention will be apparent to those skilled in the art from the following particular description and from the appended claims.

The invention attains its objects by mixing an oxide compound with the carbonate compound. The oxide compound has approximately the same decomposition pressure and temperature as the carbonate compound so that oxygen will be evolved thereby at approximately the same pressure and temperature that carbon dioxide is evolved by the carbonate compound. Suitable oxide compounds for use in the invention are for example, praseodymium oxide, magnesium superoxide or potassium permanganate. In operation, therefore, the oxygen present in the gaseous discharge path with the carbon dioxide is in such quantities that any solid carbon suboxide formed is changed immediately by "burning" to carbon dioxide or carbon monoxide and thus deposits of the light absorbing carbon suboxide on the electrodes or the glass walls of the container of the gaseous electric discharge device are prevented.

In the drawing accompanying and forming part of this specification an electric discharge device embodying the invention is shown in a side elevational view.

Referring to the drawing the electric discharge device comprises a container 1 having two electrodes 2 and 3 sealed therein one at each end thereof. Said electrodes 2 and 3 are connected by leads 4 and 5 respectively to the secondary 6 of the transformer 6, 7. A ballast resistance 19 is connected in series with the primary 7 of said transformer 6, 7. A cylindrical, metal container 9 is located in an off-set tube 8 attached to said container 1. Said container 9 is pervious to gas and is filled with a pulverized mixture of a gas evolving carbonate compound and a gas evolving oxide compound. A heating filament 11

is embedded in the mixture in said container 1 and is connected by leads 16 and 14 to the secondary 18 of the transformer 17 and 18. The primary 17 of said transformer 17, 18 is connected into the lead 4 of the electrode 2. Said transformer 17, 18 furnishes sufficient potential to heat filament 11 so as to cause an evolution of gas from the gas evolving material in said container 9 but not 10 enough to heat said container 9. Where desired, the carbonate compound and the oxide compound is pulverized, mixed and then pressed into the form of a rod and heating filament 11 is wrapped around it to cause the 15 evolution of the gas during the operation of the device.

As pointed out above the oxide compound, such as praseodymium oxide, magnesium superoxide, or potassium permanganate, and 20 the carbonate compound, such as beryllium carbonate, potassium carbonate, magnesium carbonate, or dolomite placed in said container 9 have approximately the same decomposition temperature and pressure so 25 that oxygen and carbon dioxide are generated simultaneously by said compounds respectively during the operation of the device. The oxygen present in the discharge path along with the carbon dioxide is in such 30 quantities that any solid carbon suboxide formed is changed immediately by "burning" into carbon dioxide or carbon monoxide and thus the formation of deposits of the solid, light absorbing carbon suboxide on the electrodes or the glass walls of the container 1 35 is entirely avoided.

While we have shown and described and have pointed out in the annexed claims certain novel features of the invention, it will 40 be understood that various omissions, substitutions and changes in the forms and details of the device illustrated and in its use and operation may be made by those skilled in the art without departing from the broad 45 spirit and scope of the invention.

What we claim as new and desire to secure by Letters Patent of the United States, is:

1. An electric discharge device comprising 50 a container, electrodes sealed therein, a gaseous atmosphere therein, and two or more different gas evolving materials in said container adapted to evolve gas when heated, the gas evolved by one gas evolving material 55 being adapted to transform to a gas those solid materials formed from the gas evolved by the other gas evolving material which are reactive with said first named gas.

2. An electric discharge device comprising 60 a container, electrodes sealed therein, a gaseous atmosphere therein, and a mixture of oxide and carbonate compounds in said container adapted to evolve gas when heated, the oxygen evolved by the oxide compound transforming to a gaseous state the solid carbon 65

suboxide formed from the carbon dioxide evolved by the carbonate compound, said gas evolving compounds having approximately the same decomposition temperature and pressure.

In witness whereof we have hereunto set our hands this 29th day of April 1931.

FRANZ SKAUPY.
HANS EWEST.
HANS PULFRICH.
